(57) **CLAIM**

The ornamental design for LED drumstick set as shown and described.

DESCRIPTION

FIG. 1 is an isometric view of an LED drumstick set showing my new design;

FIG. 2 is a front view thereof;

FIG. 3 is a back view thereof;

FIG. 4 is an enlarged top view thereof.

FIG. 5 is an enlarged bottom view thereof.

FIG. 6 is a left side view thereof; and,

FIG. 7 is a right side view thereof.

The dashed, broken lines represent the portions of the LED drumstick set that form no part of the claimed design.

1 Claim, 7 Drawing Sheets
